UNITED STATES PATENT OFFICE.

CURT HENNIG, OF LEIPZIG-SELLERHAUSEN, GERMANY, ASSIGNOR TO HUGO SCHNEIDER, AKTIENGESELLSCHAFT, OF LEIPZIG-PAUNSDORF, GERMANY.

WICKLESS BURNER FOR LIQUID COMBUSTIBLES.

No. 896,110.

Specification of Letters Patent.

Patented Aug. 18, 1908.

Application filed June 28, 1907. Serial No. 381,253.

To all whom it may concern:

Be it known that I, CURT HENNIG, a subject of the King of Saxony, residing in the city of Leipzig-Sellerhausen, in the Kingdom 5 of Saxony, German Empire, have invented certain new and useful Improvements in Wickless Burners for Liquid Combustibles, of which the following is a specification.

This invention relates to a wickless burner 10 in which the heat of the flame is utilized to rapidly and effectively volatilize the liquid fuel.

In the accompanying drawing: Figure 1 is a longitudinal section of my improved burner; 15 Fig. 2 is a cross section on line A—B, Fig. 1, and Fig. 3 a longitudinal section of a modification of the vaporizer.

A vaporizing tube *a*, composed of a good heat conducting material, extends from the 20 burner tube *b*, to which it is directly screwed. Vaporizing tube *a*, extends into the reservoir *c*, containing the liquid fuel. Within tube *a*, are contained a suitable number of upright sustaining tubes *d*, within and between 25 which are arranged a number of wire screens *z*, each of which is rolled up into a spiral. Screens *z*, are adapted to raise the liquid fuel by capillary action, and in conjunction with tubes *b*, and *d*, present a large 30 vaporizing surface to the fuel. The screens furthermore constitute filters for separating impurities from the fuel, and principally for separating the resinous ingredients from methylated spirit.

Vaporizer *a*, is separated from the fuel in reservoir *c*, by an insulating jacket consisting 35 of a cylinder composed of an inner shell *f*, and an outer concentric shell *g*. Shell *f*, is secured to the lower end of tube *a*, by a threaded sleeve *i*, while shell *g*, is connected at its upper end to the burner gallery by a threaded sleeve *k*. Shells *f*, *g*, also extend below the bottom of tube *a*, where they are provided with a duct *h*, which is open at both 40 ends and thus connects reservoir *c*, with the vaporizer. Cylinder *f*, *g*, is filled with a poor heat conductor, such as asbestos or air, while a second insulating air jacket is formed 45 between tube *a*, and shell *f*. Above tube *a*, is arranged a vapor chamber *p*, provided with a number of horizontal sieves *q*, which 50 retain any solid particles. Chamber *p*, carries a Bunsen burner nozzle *r*, inclosed within tube *b*. Upon tube *b*, is fitted a per- 55 forated burner head *s*, provided with means

for supporting an incandescent mantle thereon. Head *s*, and tube *b*, on becoming heated, will transmit their heat to tube *a*, as well as to tubes *d*, and rolled up wire screen *z*. In this way the fuel entering through duct *h*, will be vaporized rapidly to furnish an ample and constant supply of vapor fuel to the burner.

In Fig. 3, a ball check valve *v*, controls the flow of the fuel to the vaporizer. Here a cap *t*, having perforation *u*, is screwed to the bottom of tube *a*. Perforation *u*, is controlled by the valve *v*, movably held by keeper *w*. This valve checks the return of liquid from the vaporizer to the reservoir and thus prevents flickering.

I claim:

1. A wickless lamp, comprising a vaporizing tube, a series of inclosed tubes, a vapor chamber above said tubes, a Bunsen nozzle, 75 a non-conducting apertured jacket detachably inclosing the vaporizing tube and provided with a perforated bottom extending below the foot of the vaporizing tube, and a reservoir for liquid combustible receiving the 80 vaporizing tube and jacket, substantially as specified.

2. A wickless lamp, comprising a vaporizing tube, a series of inclosed tubes, a series of 85 rolled wire screens within and between said tubes, a vapor chamber above said tubes, a Bunsen nozzle, a non-conducting apertured jacket detachably inclosing the vaporizing tube and provided with a perforated bottom extending below the foot of the vaporizing 90 tube, and a reservoir for liquid combustible receiving the vaporizing tube and jacket, substantially as specified.

3. A wickless lamp, comprising a vaporizing tube, a series of inclosed tubes, a series of 95 rolled wire screens within and between said tubes, a vapor chamber above said tubes, a Bunsen nozzle, a non-conducting jacket having a valve-controlled duct and inclosing the vaporizing tube on the sides and bottom 100 and a reservoir for liquid combustible receiving said vaporizing tube and jacket, substantially as specified.

In witness whereof, I have hereunto signed my name in the presence of two subscribing 105 witnesses.

CURT HENNIG.
